DOOR LATCHING DEVICE

Charles Adin Fox, Oakland Village, Mo.

Application January 13, 1949, Serial No. 70,713

8 Claims. (Cl. 292—227)

1

This invention relates generally to latching devices and more specifically to latching devices for cabinets and the like which are of the type operated to the unlatched position by push buttons that project from knobs adapted for use in moving the doors of the cabinets to open and closed positions, the predominant object of the invention being to provide a latching device of the type referred to above which is of extremely simple construction and arrangement and which, because of its improved construction, is capable of performing its intended function in an improved and highly efficient manner.

Fig. 1 is a fragmentary elevational view showing the improved latching device in association with a cabinet or other structure.

Fig. 2 is a horizontal section taken on line 2—2 of Fig. 1 with the latching device shown in elevation.

Fig. 3 is a horizontal section similar to Fig. 2 but showing the latching device largely in section.

Fig. 4 is a horizontal section similar to Fig. 3 but with the latching device shown in its unlatched position.

Fig. 5 is a fragmentary section taken on line 5—5 of Fig. 4.

Fig. 6 is a perspective view of a part of the improved latching device of this invention.

In the drawing, wherein is shown for purposes of illustration, merely, one embodiment of this invention, A designates the improved latching device generally. In order to provide for a complete understanding of the invention the improved latching device is illustrated in the drawing in association with a structure that includes a housing portion B and a door C, it being understood that such structure may be any one of a great variety of structures into the interiors of which access may be had through door openings closed by movable doors, or other closure members. The improved latching device A includes an elongated tubular member 1 which is extended through an opening 1' formed through the door C with which the latching device is associated, the outer portion of the tubular member being extended outwardly beyond the outer face of the door, as is shown to good advantage in Figs. 3 and 4. Also, the tubular member 1 is provided with external screwthreads which extend throughout a considerable portion of the length thereof and to the outer end of said tubular member.

At its inner portion the tubular member 1 is split longitudinally from the inner end thereof

2

a distance inwardly of said tubular member, and said split end portion of said tubular member is shaped to provide a bifurcated portion 2 having spaced legs 2', as is shown to good advantage in Fig. 5. Mounted on the bifurcated end portion 2 of the tubular member 1 is a hollow element 3 which serves as a combined housing and latching element, said element 3 receiving therewithin said bifurcated end portion 2, and said element 3 being pivotally connected to said bifurcated end portion 2 of said tubular member by a pivot pin 4 which extends through aligned apertures formed through opposed side walls of the element 3 and through the spaced legs 2' of said bifurcated end portion of the tubular member 1.

The element 3 is shaped as is shown to good advantage in Fig. 6; that is to say, said element is provided with opposed side walls 3a, which are in the side walls referred to above as being apertured to receive portions of the pivot pin 4, and said element 3 is provided with a marginal wall 3b which is shaped as is shown to good advantage in Figs. 2, 3, and 4. Also, a torsional coil spring 5 is coiled about the pivot pin 4, one end portion of said coil spring being arranged in contact with the inner face of the wall 3b of the element 3, while the opposite end portion of said torsional coil spring contacts with an upper portion of the inner face of the tubular member 1. Because of the arrangement of the torsional coil spring 5 as described above, the element 3 is urged by said coil spring in the direction indicated by the arrow in Fig. 2.

The portion of the tubular member 1 which extends outwardly beyond the door C has screwthreadedly mounted thereon a knob 6 whose inner face contacts closely with an outer face portion of the door, and screwthreadedly mounted on said tubular member 1 inwardly of the bifurcated portion 2 thereof is a nut 7, said nut having a tapered, tubular extension 7' which is seated in an end portion of the opening 1' formed through the door C. Extended through the tubular member 1 is an operating element 8 which is preferably in the form of a length of rod, or relatively rigid wire, said operating element being bent at its inner end as is indicated at 8a in Figs. 3 and 4 and the outer portion 8b of said bent portion 8a is extended through an aperture 8c which is formed through the marginal wall 3b of the element 3. The opening 6a through the knob 6 is of slightly greater diameter at the outer portion of said knob and this enlarged opening portion 6b receives a push button 9, said push

button being provided with an opening 9' formed longitudinally thereof which frictionally receives an outer end portion of the operating element 8.

The housing portion B, shown in Figs. 2, 3 and 4, is provided with a keeper 10 which is formed from a strip of material bent as illustrated in the views referred to above, said keeper comprising a leg portion 10a which is arranged in contact with the rear face of the housing portion B, a leg 10b which is arranged in contact with an edge of said housing portion B that defines a part of a door opening which is closed by the door C, and a bent double, rearwardly extended portion 10c. The keeper 10 is secured to the housing portion B by suitable fastening elements 11 which extend through apertures formed through the legs 10a and 10b of said keeper and into the housing portion B.

The task of installing the improved latching device of this invention in association with a door is extremely simple and is accomplished without the use of screws or other fastening devices frequently employed for securing latching devices in place. In other words; the installation of the latching device is accomplished by first forming the opening 1' through the door, and by passing the tubular member 1 through said opening. The knob 6 is then screwed inwardly on the outwardly extended forward portion of the tubular member 1 until the inner end face of the knob contacts the outer face of the door after which the knob is rotated additionally so as to cause the tapered, tubular extension 7' of the nut 7 to be drawn into the end portion of the opening 1' of the door and to cause the nut 7 to contact with the inner face of the door. The element 3 is then held by one hand and the push button 9 is forced onto the outer end portion of the operating element 8 within the opening portion 6b of the knob 6 so as to provide tight frictional engagement between the end portion of the operating element and the push button.

When the keeper 10 has been installed in an obvious manner the latching device is ready for use, and when in such use the door C is moved toward its closed position a portion of the curved outer face of the wall 3b of the element 3 will contact with the outer end portion of the leg 10b of the keeper 10 with the result that said element 3 will be rotated about the pivot pin 4 in the reverse direction to that indicated by the arrow in Fig. 2. When the door reaches its fully closed position the torsional coil spring 5 moves the element 3 to the position in which it is shown in Fig. 3 where it overlaps the portion 10c of the keeper so as to latch the door in its closed position. When it is desired to unlatch the door the knob is grasped by certain fingers of the hand and the push button is moved inwardly by the thumb of the same hand with the result that the element 3 will be moved to the position in which said element is shown in Fig. 4 to permit the door to be drawn open. It is to be noted that the portion 10c of the keeper 10 may be conveniently bent slightly with the aid of a pliers, when this is necessary, so as to cause the element 3 to properly engage said keeper portion 10c when the door is latched.

It is to be noted that the center of the radius of the forward curved portion of the element 3 is not located at the pivot 4 but, instead, such radius is shorter at the right-hand end thereof, as said element is illustrated in Fig. 2, than at the opposite end of said radius. Because of this

arrangement a tightening effect is produced when the element 3 swings in the direction of the arrow in Fig. 2 under the influence of the torsional coil spring 5 and with respect to the portion 10c of the keeper 10, which causes the door C to be drawn to a tightly closed position relative to the housing portion C so as to eliminate rattling of the door.

I claim:

1. A latching device comprising a tubular member adapted to be extended through an opening formed through a door, said tubular member being of such length as to cause an inner portion thereof to be extended inwardly of a door with which said tubular member is associated and to cause an outer portion thereof to be extended outwardly of such a door, a knob mounted on said outer portion of said tubular member, a hollow latching element which embraces said inner portion of said tubular member, means for pivotally connecting said latching element to said inner portion of said tubular member, an operating element connected to said latching element and extended through said tubular member, and a push button supported by said knob and connected to said operating element.

2. A latching device comprising a tubular member adapted to be extended through an opening formed through a door, said tubular member being of such length as to cause an inner portion thereof to be extended inwardly of a door with which said tubular member is associated and to cause an outer portion thereof to be extended outwardly of such a door, a knob mounted on said outer portion of said tubular member, a hollow latching element which embraces said inner portion of said tubular member, means for pivotally connecting said latching element to said inner portion of said tubular member, an operating element connected to said latching element and extended through said tubular member, and a push button supported by said knob and connected to said operating element.

3. A latching device comprising a tubular member adapted to be extended through an opening formed through a door, said tubular member being of such length as to cause an inner portion thereof to be extended inwardly of a door with which said tubular member is associated and to cause an outer portion thereof to be extended outwardly of such a door, a knob mounted on said outer portion of said tubular member, a hollow latching element which embraces said inner portion of said tubular member, means for pivotally connecting said latching element to said inner portion of said tubular member, torsional spring means which tends to rotate said latching element in one direction, an operating element connected to said latching element and extended through said tubular member, and a push button supported by said knob and connected to said operating element.

4. A latching device comprising a tubular member adapted to be extended through an opening formed through a door and having a bifurcated inner end portion which is adapted to extend inwardly of a door with which said tubular member is associated and an outer portion which is adapted to extend outwardly of such a door, a knob mounted on said outer portion of said tubular member, a hollow latching element which embraces said bifurcated inner portion of said tubular member, means for pivotally connecting said

latching element to said bifurcated inner portion of said tubular member, an operating element connected to said latching element and extended through said tubular member, and a push button supported by said knob and connected to said operating element.

5. A latching device comprising a tubular member adapted to be extended through an opening formed through a door and having a bifurcated inner end portion which is adapted to extend inwardly of a door with which said tubular member is associated and an outer portion which is adapted to extend outwardly of such a door, a knob mounted on said outer portion of said tubular member, a hollow latching element which embraces said bifurcated inner portion of said tubular member, means for pivotally connecting said latching element to said bifurcated inner portion of said tubular member, spring means which tends to rotate said latching element in one direction, an operating element connected to said latching element and extended through said tubular member, and a push button supported by said knob and connected to said operating element.

6. A latching device comprising a tubular member adapted to be extended through an opening formed through a door and having a bifurcated inner end portion which is adapted to extend inwardly of a door with which said tubular member is associated and an outer portion which is adapted to extend outwardly of such a door, a knob mounted on said outer portion of said tubular member, a hollow latching element which embraces said bifurcated inner portion of said tubular member, means for pivotally connecting said latching element to said bifurcated inner portion of said tubular member, torsional spring means which tends to rotate said latching element in one direction, an operating element connected to said latching element and extended through said tubular member, and a push button supported by said knob and connected to said operating element.

7. A latching device comprising a tubular member adapted to be extended through an opening formed through a door and having a bifurcated inner end portion which is adapted to extend inwardly of a door with which said tubular member is associated and an outer portion which is adapted to extend outwardly of such a door, a knob mounted on said outer portion of said tubu-

lar member, a hollow latching element which embraces said bifurcated inner portion of said tubular member, means comprising a pivot pin which extends through portions of said bifurcated portion of said tubular member and portions of said latching element for pivotally connecting said latching element to said bifurcated inner portion of said tubular member, spring means which tends to rotate said latching element in one direction, an operating element connected to said latching element and extended through said tubular member, and a push button supported by said knob and connected to said operating element.

8. A latching device comprising a tubular member adapted to be extended through an opening formed through a door and having a bifurcated inner end portion which is adapted to extend inwardly of a door with which said tubular member is associated and an outer portion which is adapted to extend outwardly of such a door, a knob mounted on said outer portion of said tubular member, an abutment element having a tapered portion which is mounted on said tubular member and is adapted to abut against a face of a door with which said tubular member is associated with said tapered portion thereof seated in an end portion of the opening of the door through which said tubular member extends, a hollow latching element which embraces said bifurcated inner portion of said tubular member, means for pivotally connecting said latching element to said bifurcated inner portion of said tubular member, an operating element connected to said latching element and extended through said tubular member, and a push button supported by said knob and connected to said operating element.
